UNITED STATES PATENT OFFICE.

CHARLES T. DAVIS, OF BROOKLYN, NEW YORK.

SEALED CONTAINER OF SURGICAL LIGATURES AND METHOD OF PREPARING SAME.

1,168,173.

Specification of Letters Patent. Patented Jan. 11, 1916.

Application filed April 20, 1915. Serial No. 22,643.

To all whom it may concern:

Be it known that I, CHARLES T. DAVIS, a citizen of the United States, residing at Brooklyn, in the county of Kings and State 5 of New York, have invented certain new and useful Improvements in Sealed Containers of Surgical Ligatures and Methods of Preparing Same, of which the following is a specification.

10 This invention relates to surgery, and particularly to the sterilization, storing, and preservation ready for use of surgical ligatures or sutures, such as employed by surgeons for stitching wounds and for tying 15 arteries.

While features of the invention may be applicable in the storing and preserving of ligatures of other kinds, by way of illustration, I have described the invention as applied to ligatures composed of animal tissue, known as catgut. Such ligatures, of course, must be sterilized to prevent any possible 20 infection of the wound. The most generally employed method now in use for sterilizing, storing, and preserving catgut ligatures necessitates the use of two different liquids, one for sterilizing, and one for storing. Under such method, the ligature is first sterilized by immersing in a heated bath 25 of a suitable liquid such as cumol, having a comparatively high boiling point. The surplus cumol is then rinsed off, and the ligature inclosed in a sealed tube containing 30 a lighter and more volatile storing liquid such as chloroform or alcohol. There are many objections to the use of these two latter substances, and there is also grave objection to the present method of sterilization 35 because it renders possible, and in fact, 40 likely, the accidental contamination of the ligatures from the necessary handlings during the several steps of manufacture.

The principal object of the present invention is to produce, as an article of manufacture, a sealed tube or container inclosing a ligature having superior qualities, such qualities arising both from the improved process of preparing and sterilizing the ligature, and from the character of the storing 50 liquid employed. To this end, I employ a liquid of such a nature that it will serve for both sterilizing and storing purposes, thus eliminating entirely the use of two separate liquids, and avoiding any possibility of accidental contamination of the ligatures because permitting the entire process of heat

sterilization to be conducted after the tubes or containers are hermetically sealed.

In practising my invention, I sterilize the ligature entirely after the tube is sealed, as 60 suggested above, and one of the objects of my invention is to produce tubes or containers of ligatures wherein this sterilization can be very effectively carried on after the tubes or containers are sealed, while by 65 the same procedure of sealing the tubes or containers preliminary to sterilization, the possibility of accidental contamination either during or subsequent to the process of sterilization is entirely eliminated, thus ren- 70 dering positive the assurance of sterility, and coincidentally effecting a great economy in the amount of time and skilled effort otherwise required when conducting the process of sterilization and the handling of 75 the ligatures under aseptic conditions and amid sterile environments, as is necessary when employing the method heretofore in vogue, (i.e., the sterilization of the ligatures before the sealing of the tubes and the subsequent filling of the tubes with their content of sterile storing fluid).

A further specific object of the invention is to provide an improved method of sterilization, whereby the heated storing fluid is 85 forced into the pores and interstices of the ligature under pressure; thereby sterilizing the ligature not only on the surface, but also throughout the body thereof.

Further objects of the invention will appear more fully hereinafter.

The invention consists in those features and combinations of features described in detail hereinafter, all of which contribute to produce an efficient tube or container of 95 ligatures.

As illustrating the method of carrying out my invention, reference is had to the accompanying drawings, in which,

Figure 1 is a side elevation of a tube embodying my invention; and, Fig. 2 is a view similar to Fig. 1, but illustrating the process of sterilizing the ligature within the tube.

Before proceeding to a detailed description of my invention, consideration should be given to the defects of chloroform and alcohol when used as storing, preserving, or sterilizing fluids in ligature tubes. Chloroform has been found objectionable for these purposes for many reasons, chief among 105 which are the following: First—Chloroform breaks down under comparatively moderate

- heat into chlorin and hydrochloric acid, both of which exert an extremely harmful effect upon the ligatures. Second—Under the influence of sunlight, free chlorin, hydrochloric acid and carbonyl chlorid (phosgene) are liberated, the latter product in particular being extremely objectionable. Third—The disagreeably irritating and harmful effect of chloroform upon the tissues. Fourth—The inadequately low boiling point of chloroform, which prevents the successful application of the temperature necessary for the sterilization of the tubes after being sealed. Fifth—The susceptibility of chloroform to deterioration from age. Sixth—Chloroform can hold water in solution, which is very harmful to the ligatures, particularly to that kind of ligature most widely used, namely, catgut, for as is well known, the slightest degree of moisture tends to convert the collagen in the catgut into gelatin, with the result that when the catgut is subjected to thermal sterilization, it becomes brittle, weakened, and twisted. Alcohol is objectionable for many reasons, chief among which are its low-boiling point, its inefficacy as a solvent of the fatty matter of the ligatures, and for the further reason that, as is well known, alcohol has a strong affinity for water, and hence it is difficult to secure alcohol which is perfectly free from water. As above stated, the presence of even a minute quantity of water in the storing liquid tends to convert the collagen of the gut into gelatin, with the result that when the gut is subjected to any adequate sterilizing temperature, such as 100° C. (212° Fahrenheit) or over, it becomes brittle, weakened, and twisted. In order to overcome the difficulties and objections mentioned above, the combination sterilizing and storing liquid employed should possess the following characteristics: It must have a boiling point sufficiently high to permit of sterilization of the contents of the sealed tube at an adequate temperature, and at the same time, sufficiently low to admit of rapid evaporation when the ligature is removed from the tube; it must be absolutely non-irritating to the tissues of the body; it must be entirely stable and not subject to deterioration under the influence of heat, light, or time; moreover, it must be incapable of holding water in solution, and should even preferably be water-repellant. I have discovered that the benzene series of hydrocarbons, and especially the lower methyl-substitution products thereof, answer the above requirements to a remarkable degree. Benzol itself, having the formula C_6H_6 , may be employed to advantage, as well as mono-methyl benzene $C_6H_5CH_3$, or any of the three di-methyl benzenes. The mono-methyl product is known as toluol or toluene, and the di-methyl products as

ortho-, meta-, and para-xylool or xylene. Mixtures of any or all of these substances may also be used successfully.

The above compounds, being in the nature of light, volatile oils, will not hold water in solution, and are absolutely stable and inert at ordinary temperatures. Moreover, they are powerful solvents for oils and fats, and are therefore very efficient in removing the fats and fatty acids occurring in catgut ligatures, and which are irritating to the tissues of the body.

In producing a tube of ligatures according to my invention, I prefer to provide a tube or container 1, of any suitable substance, such as glass, which will resist the high temperature necessary for sterilizing the contents. The first step necessary is to insert the strand or strands of catgut or other ligature material, suitably wound or coiled, within the tube or container. Next, the moisture is removed from the ligature by any suitable dehydrating process, this being a very necessary step for the reason previously explained. Then I place within the tube or container a small quantity of the storing fluid 2. I prefer to use a volume of this liquid equivalent to only a small fraction of the volume of the tube, for reasons which will appear more fully hereinafter. I then slightly heat the tube so as to cause vaporization of the liquid, and then while the upper part of the tube is filled with the vapors of the liquid, I hermetically seal the tube, preferably by fusing and closing its end in a well known manner. By slightly heating the tube and simultaneously sealing it in this way, I insure that a vacuum is created within the tube upon the condensation of the vapors. With the tube sealed in this way and containing this substance, it is also assured that the interior of the tube will be devoid of water, because the presence of water in the substance is immediately indicated by the substance itself, which, as suggested above, will not mix with water.

After the tube or container has been sealed as suggested, I then effect the sterilization by heating it to a sufficiently high temperature to sterilize the contents. The substance toluol boils at about 111° centigrade; the product benzol, the base or nucleus of the benzene or aromatic series of hydrocarbons, boils at about 80° C.; while the di-methyl benzenes, ortho-xylene, meta-xylene, and para-xylenè, boil at from about 137° to 143° C. The substances named, and various mixtures thereof in different proportions, all have a boiling point between 80° C. and 143° C., and these temperatures mark substantially the practical limits within which the invention can be successfully carried out, although in some cases, a product having a boiling point even below 80° C. may be employed. Furthermore, these substances have

the characteristic of being highly volatile, which insures that when the tube is broken for use by the surgeon the substance quickly evaporates; but if it should happen that the ligature is applied so quickly as to prevent perfect evaporation, the substance will not have any deleterious effect whatever upon the wound, but will simply have a slight cooling effect due to evaporation. These

5 substances leave no residue upon evaporation, so that any possibility of irritation of the wound from foreign bodies, (a "foreign-body irritation" as it is known among surgeons) is completely avoided.

10 The temperature employed for sterilization varies with the nature of the particular liquid used, but is always substantially above the normal boiling point of such liquid, and in no case less than 100° C.

15 For example, in using toluol, which boils at 232° F. (111° C.)

20 a temperature of between 240° and 250° F. would be employed, while with benzol, the

25 temperature would not run so high. In each instance, the temperature is raised to such a

30 point as will produce a pressure within the tube sufficient to force the vapor well into the pores of the ligature, and thoroughly impregnate the same. Care must be exercised, however, that the temperature does not rise

35 too high, as there is danger of bursting the tube by excessive pressure. The pressure is

40 automatically regulated to some extent, perhaps, by reason of the fact that as the pressure rises, it naturally tends to check ebullition and prevent the further giving off of

45 vapor.

50 By reason of the fact that I employ a small volume of liquid as suggested, there is a relatively large space in the tube above the

55 surface of the liquid, which will become filled with dense vapors when the proper

60 degree of heat is applied, and the effect of this is to force the vapors under pressure

65 through the capillary interstices of the ligature, and in such a way as to impregnate

70 such interstices or cells of the ligature with the vapors of the substance, thus not only

75 contributing to the most thorough sterilization of the ligature, but at the same time in-

80 creasing its flexibility, the latter a most im-

85 portant consideration. The liquid within

90 the tube is, of course, in contact with the

95 ligature, but the ligature preferably extends

100 up to a height in the tube so that a large

105 part of the ligature may be exposed above

110 the level of the liquid, it being understood

115 that the vapor created by boiling the fluid

120 will rise and completely envelop the ligature, thus effecting, with but a very small

125 quantity of liquid, equally as efficient sterilization as though the ligature were com-

130 pletely submerged. This effects a decided

135 economy in the cost of such tubes or

140 containers of ligatures, because of the relatively

145 small quantity of the fluid employed.

My invention renders possible the very desirable procedure of sterilizing the exterior of the tubes by boiling in water along with the surgical instruments preliminary to operating.

70

What I claim is:

1. As a new article of manufacture, a hermetically sealed glass container holding a ligature with a highly volatile hydrocarbon liquid within said container having a volume 75 which is a fraction of the volume of said container, the interior of said container being devoid of water, and substantially devoid of air.

2. As an article of manufacture, a hermetically sealed glass tube containing a ligature, and a liquid hydrocarbon having a boiling point between 80° and 143° C.

3. As an article of manufacture, a hermetically sealed glass tube containing a ligature and a liquid incapable of mixing with water, such liquid having a boiling point sufficiently high to admit of the tube being heated to at least 100° C. without generating dangerous pressures within the same.

4. As an article of manufacture, a hermetically sealed glass tube containing a ligature, and a stable, volatile, preserving and storing liquid, said liquid having a volume 95 which is a small fraction of the volume of the tube, whereby a relatively large space is presented within the tube to hold the vapors of said liquid, when the tube is heated.

5. The method of preserving surgical ligatures which consists in placing the ligature 100 in a container together with a quantity of a stable, inert storing liquid, the volume of the liquid being less than that of the container, heating the container until the liquid gives off vapor in such quantity as to expel 105 the air, and then sealing the container while filled with the vapor, whereby air is substantially excluded.

6. The method of sterilizing and storing surgical ligatures which consists in inclosing 110 the ligature in a sealed container together with an inert, volatile liquid, the volume of the liquid being only a small fraction of that of the container, and then heating the container, whereby the container, above the liquid is filled with vapors which envelop the ligature.

7. The method of sterilizing and storing surgical ligatures which consists in inclosing 120 the ligature in a sealed container together with a stable, inert, preserving liquid, the volume of the liquid being only a small fraction of that of the container, and then heating the container to a point substantially above the boiling point of the inclosed liquid, 125 whereby vapor pressure is generated within the container, and the vapor thus caused to penetrate the pores of the ligature.

8. The herein described method of preserving surgical ligatures and the like which 130

consists in placing the prepared ligature in a suitable container, open at one end, partially filling such container with a liquid having a boiling point above 80° centigrade and capable of dissolving fats, hermetically sealing the container and then subjecting the sealed container and its contents to a suitable sterilizing heat, above the boiling point of said liquid.

10 9. The hereindescribed method of treat-

ing surgical ligatures which consists in subjecting them to the action of a hydrocarbon-vapor under pressure, and above a temperature of 100° C.

In testimony whereof I have affixed my 15
signature, in presence of two witnesses.

CHARLES T. DAVIS.
